CHARLES A. SAWTELLE, OF DETROIT, MICHIGAN, ASSIGNOR OF ONE-HALF TO ARMIN A. DARMSTAETTER, OF DETROIT, MICHIGAN

CARBURETOR AND METHOD OF CARBURETING

Application filed October 21, 1926. Serial No. 143,110.

This invention relates to carburetors and methods of carbureting.

One of the objects of the invention is to accurately regulate the delivery of fuel to an internal combustion engine, by providing a plurality of restricted passages leading from a source of fuel, and exercising a control of said passages, in common, by an element adapted to successively establish communication of said passages with the intake manifold of the engine.

Another object is to restrict said passages differentially, and to an extent decreasing in the order that said passages are adapted to successively communicate with the engine, whereby as the number of said passages communicating with the mixing chamber of the carburetor is increased, the resulting decrease in the vacuum intensity acting within said passages is compensated for by the lessened restriction and the consequent increased responsiveness of the fuel.

Still another object is to provide a common means for restricting to a very definite degree a plurality of passages leading from a source of fuel to an engine or mixing chamber, and to provide for removal and replacement of said means, so that by a substitution the amount of restriction of all of the passages may be varied.

A further object is to produce initially an excessively rich mixture of fuel and air, to further dilute said mixture in the course of its flow to the engine, and to regulate the volume of the flowing mixture and of the air with which it is further diluted by a common control element.

A still further object is to provide for determining the volume of the final mixture by individual regulation of its fuel and air components.

It is an object of the invention also to provide for heating the mixture, while excessively rich, to reduce the fuel component to a gaseous form, and subsequently diluting and at the same time cooling the mixture by adding a regulated volume of unheated air, whereby the final mixture which is delivered to the engine is gaseous as regards its fuel component but is not heated to an extent to

objectively reduce the effective volume which may be received by an engine cylinder.

The invention further consists in a provision for automatically regulating the heating effect exerted by the exhaust gases of an engine upon a plurality of fuel conduits by arranging said conduits in a certain relation to the flow of such gases.

These and various other objects are attained by the construction exemplified in the accompanying drawings, and hereinafter fully described.

In said drawings:

Figure 1 is a view in side elevation of the upper portion of an explosive engine, showing the intake and exhaust manifolds thereof, in association with the improved carburetor.

Figure 2 is a view showing the two manifolds in end elevation and also showing in elevation the inlet end of the mixture heating chamber.

Figure 3 is a longitudinal sectional view of the carburetor taken upon the line 3—3 of Figure 2.

Figure 4 is a vertical elevational view of the float chamber and initial carburetion means, partly in section on line 4—4 of Figure 5.

Figure 5 is a transverse vertical sectional view taken upon line 5—5 of Fig. 4, and showing primarily the fuel discharge passages of the float chamber.

Figure 6 is a perspective view of a sheet metal plate adapted to be mounted upon the float chamber and formed with a series of openings differentially restricted for predetermineding the flow from the various outlets of the float chamber.

Figure 7 is a detail plan view, partly in section, of an air cooled fitting, adapted to connect the initial carburetion means and the heater, and provided for heating the explosive mixture delivered to the engine upon starting the same.

Figure 8 is a vertical section taken upon line 8—8 of Fig. 1, showing the fuel inlets of the mixing and throttle chamber.

Figure 9 is a cross section view of said mixing and throttle chamber, taken upon the line 9—9 of Fig. 8.

Figure 10 is a perspective view of the throttle member.

Figure 11 is a cross sectional view of the heating chamber and adjacent portion of the exhaust manifold.

Figure 12 is a fragmentary view in side elevation of a provision for operating the primary fuel control valve of the device from a governor which responds to the speed of the engine to which said device is auxiliary.

In these views the reference character 1 designates an internal combustion engine, 2 the intake manifold thereof, and 3 the exhaust manifold. To the inner face of the manifold 3, there is secured a fuel heating chamber 4, into the upper portion of which the exhaust gases are diverted by a baffle plate 5 formed in the lower or outlet portion of said manifold see Figure 11. From the chamber 4, the exhaust gases escape back to the manifold 3, below said baffle plate, discharging finally from the manifold by way of the exhaust conduit 6.

To one end of the heating chamber 4, there is secured a fuel-supplying float chamber 7, which however is spaced from said heating chamber by a fitting 8. (See Figures 4 and 5.) A pair of bolts 9 serve to secure both said float chamber and fitting to the heating chamber. The float chamber is formed with a projection 10 which the bolts 9 engage, and in said projection is mounted a row of vertical fuel induction tubes 11 opening at their lower ends into the fuel space of said chamber, below the normal fuel level therein. Upon the projection 10 there is secured by screws 12 a cap 13, between which and said projection there is clamped a sheet metal plate 14 formed with a row of slots 15, which are of a restricted width and which may progressively vary from one end of the row to the other. Said slots at corresponding ends are enlarged to communicate with the upper extremities of the fuel tubes 11, and have their other ends likewise enlarged to communicate with a row of inclined passages 16 in the projection 10. The passages 16 extend to that face of the projection 10 which is adapted to be clamped against the fitting 8, and are adapted to register with a row of horizontal fuel passages 17 in said fitting. Said fitting is suitably ribbed to expedite its dissipation of such heat as it may receive by conduction from the heating chamber 4.

Within said heating chamber, there is arranged a row of spaced horizontal fuel tubes 18, extending from end to end of said chamber. At one end of said chamber, said tubes are mounted in openings 19, which when the fitting 8 is clamped against said end, register with the passages 17 of said fitting. The top and bottom walls of the heating chamber as they project from the exhaust manifold converge toward said tubes, so that the exhaust gases are deflected into more intimate

contact with said tubes the further they are projected into said chamber.

To the other end of the heating chamber 4, there is clamped by means of bolts 20 a mixing and throttle chamber 21. The latter chamber is formed with a horizontal row of fuel passages 22 which, when said chamber is clamped in its position of use register with the outlet ends of the tubes 18, and which open into the mixing space 23 of said chamber, see Figures 7 and 8. Into the space 23 there also opens a horizontally elongated air inlet port 24 which opens downwardly to the atmosphere, and from said space in an opposite relation to the fuel passages 22, there opens a mixture outlet 25, to which is connected a goose-neck portion 26 of the intake manifold.

A hollow cylindrical control valve 27 is rotatably fitted within the chamber 21, and is provided with a control stem 28, passing through the end cap 29 of said chamber and carrying a suitable actuating arm 30. Said valve is formed with an opening 31 through its wall elongated in the direction of the valve axis, said opening forming an admission port both for fuel and for diluting air. The advance edge 32 of said opening is of spiral form, so that an opening movement of said valve registers said opening 31 first with a fuel passage 22 at one end of the row and then successively registers said opening with the remaining fuel passages. While one portion of the edge 32 is riding across the fuel inlets 22, exercising control thereof, an end portion of said edge is riding across the air inlet port 24, and admitting air to the opening 31 in a definite proportion to the fuel which is entering through the uncovered fuel passages. In said valve 27 there is further formed a mixture outlet 33, proportioned to maintain full communication between the mixing space 23 and the mixture outlet 25 in all positions of said valve. It is preferred to form the valve with a deflector wall 33a extending integrally inward from the spiral edge of the opening 31 and then extended across said opening. Said deflector wall compels the air incoming through the port 24 to flow across such of the fuel inlet passages 22 as are uncovered so that there is an intimate commingling of said air and incoming fuel prior to admission of the same to the mixing space 23.

As the fuel flows through the passages 16, it is preferred to mix with said fuel a regulable quantity of air, producing a mixture that, for explosion purposes, is excessively rich. It is this rich mixture then that is delivered through the heated tubes 18, and into the mixing chamber through the passages 22. Thus the cap 13 has the nature of a valve casing wherein is mounted a rotative sleeve valve 34, corresponding ends of said valve and casing being open for admis-

sion of air to said valve. (See Figure 5.) A row of ports 35 are formed in said valve and a corresponding row of ports 36 are formed in the casing 13, the ports 36 being in fixed registration with the passages 16 through the slots 15 of the plate 14.

By rocking the valve 34 the ports 35 thereof may be registered more or less with the ports 36 to regulate the volume of air admitted to 10 the passages 16, responsive to the suction effect of the engine.

The position of the air control valve 34 may be so governed by the speed of the engine as to prevent any impoverishment of the mixture 15 resulting when the engine speed drops off due to a load increase or to adverse traction conditions. (See Figure 12.) Thus an actuating stem 38 for the valve 34 is passed through the closed end of the casing 13 and an arm 20 39 mounted upon said stem is connected by a swinging rod 40 to a centrifugal governor 41 of any ordinary construction, mounted as shown upon the cam shaft 42 of the engine or upon any other shaft driven by 25 the engine. The collar 43 engaged by the rod 40 is loosely mounted upon the shaft 42 but is so connected to the governor as to undergo a slight sliding travel upon said shaft responsive to variations in the speed of said shaft. This sliding travel of said collar acts through the rod 40 to swing the arm 39 through a small arc responsive to speed variations of the engine, and the resultant rocking of the valve 34 is such as to gradually 30 reduce the air supply to the passages 16 as the engine speed is reduced. Thus the weakening of the vacuum effect resulting from the reduction of engine speed is compensated for by a more complete transmission of said effect to the fuel supply chamber 7.

When an engine equipped with the described carburetor is being started, the described means for heating the fuel tubes 18 will not be effective and it is preferred, therefore to make a special provision for heating and gasifying the fuel under starting conditions. Referring particularly to Fig. 7, 44 is an electrical resistor which is disposed within those two passages 17 of the fitting 50 8 which are, by the initial opening movement of the valve 27, placed in communication with the intake manifold. As shown, said resistor is preferably U-shaped, with portions extending in the two said passages, and the electrical circuit including said resistor is established in any suitable manner, as is diagrammatically illustrated in Fig. 7. When the engine has been started and has warmed up 55 sufficiently to make the heating chamber 4 effective, the switch 45 controlling said circuit may be opened.

A very accurate regulation of the flow of fuel into the mixing chamber 23 under differing operating conditions of the engine is

made possible by establishing such flow through a considerable number of restricted passages which may be conveniently opened to said mixing chamber in a desired succession by means of a single control valve 27 70 through said chamber.

Furthermore the subdividing of the flowing fuel, as has been described, permits a more effective heating action of the exhaust gases upon said fuel. 75

The initially enriched mixture may more rapidly and thoroughly be commingled with the air admitted to the mixing chamber than would be the case if the fuel were delivered to said chamber undiluted, and this is particularly the case when the fuel element of the enriched mixture is gasified, as described, prior to admission of said mixture to said chamber. 80

It is to be noted that the described invention regulates the volume of the final mixture delivered to the engine by a control exercised upon the admission of the excessively rich mixture and the air to the mixing chamber 23 a predetermined ratio being maintained 85 between the rich mixture inflow and the air inflow. In the less accurate practice now generally followed, the flow of the final mixture is regulated by a throttle in the outlet from the mixing chamber, and it is attempted 90 to control the volumes of fuel and air admitted to the mixing chamber by pressure conditions therein. 95

The plate 14 with its accurately formed slots 15 forms a very simple means for definitely regulating the fuel flow from the float chamber. The fact that this plate is readily removable permits plates varying slightly in thickness, to be interchangeably used according to the particular operating conditions which will be encountered by a given engine or group of engines. Thus if the thickness of the plate 14 is increased, this will provide for an increased fuel flow 100 through the multiple fuel feed passages 105 leading to the mixing chamber 23, whereas a reduction of the fuel flow will result from use of a thinner plate 14. While utility of the plate 14 is not, by any means, based 110 solely on the successively varying areas of the slots 15, this variation is desirable as a compensation for the reduction of vacuum 115 intensity tending to accompany an increasing delivery of mixture to the engine. Thus the full flow which the valve member 27 initially establishes (under idling conditions) will be through the most restricted 120 of the slots 15. As said valve member is increasingly opened, fuel will flow through 125 an increasing number of the slots 15 and the capacity of the individual slots thus brought into use increases as their number increases, thus compensating for the reduction of the vacuum effect which accompanies 130

the opening travel of the valve member 27. What I claim is:

1. In a carburetor, the combination with an engine intake manifold, of a liquid fuel container having a plurality of restricted outlets, individual fuel delivery connections between said outlets and manifold, and a common control means for the flow through said connections, and a member differentially restricting said fuel connections in advance of said control means.
2. In a carburetor, the combination with a mixing chamber, of a plurality of liquid fuel delivery connections leading to said chamber, a common means in advance of said chamber for differentially restricting said connections, and means within said chamber, for controlling the fuel delivery through said connections independently of said restricting means.
3. In a carburetor, the combination with a mixing chamber having an air inlet and a liquid fuel chamber having a plurality of outlets, of means carried by said chamber for differentially restricting said outlets, fuel delivery connections from each of said outlets to said mixing chamber, and a common means within said mixing chamber for controlling said fuel connections and air inlet.
4. In a carburetor, the combination with a mixing chamber having an air inlet and having a plurality of liquid fuel inlets, of means for forming an excessively rich fuel mixture and for delivering the same to said fuel inlets.
5. In a carburetor as set forth in claim 4, means within said mixing chamber for controlling said fuel inlets and air inlets in common.
6. In a carburetor as set forth in claim 4, means within said mixing chamber for regulating the inflow of air and fuel through said inlets and for maintaining a definite ratio between the inflow of air and of fuel.
7. In a carburetor, the combination with a mixing chamber, of a plurality of fuel delivery passages opening into said chamber, means for admitting a restricted volume of air to each of said passages, and a common means for regulating the admission of such air.
8. In a carburetor, the combination with a liquid fuel container and a plurality of liquid fuel delivery connections leading from said container, of a removable and replaceable member definitely restricting all of said passages, and carried by said fuel container.
9. In a carburetor, the combination with a plurality of fuel passages, of a sheet metal stamping formed with openings registering with and restricting said passages.
10. In a carburetor, the combination with a plurality of fuel passages, of a sheet

metal stamping formed with openings registering with said passages and differentially proportioned to effect a definite differential restriction of said passages.

11. In a carburetor, the combination with a liquid fuel container having a plurality of outlet passages, of a valve controlling the admission of air to said outlet passages, a casing for said valve mounted upon said fuel container, and a member clamped between said container and valve casing, effecting a definite restriction of all of said passages.

12. In a carburetor, the combination with a liquid fuel container having a plurality of outlet passages, of a valve controlling the admission of air to said passages, a casing for said valve mounted upon the fuel container, and a member clamped between said container and valve casing formed with a plurality of openings for connecting portions of each of said passages, the admission of air to said passages being effected through said openings.

13. In a carburetor, the combination with a liquid fuel container having a fuel outlet passage, of a valve controlling the admission of air to said passages, a casing for said valve mounted upon said fuel container, and a member clamped between said container and valve casing effecting a definite restriction of said passage.

14. In a carburetor, the combination with a mixing chamber having an air inlet, of means for forming an excessively rich mixture of fuel and air and delivering the same to said mixing chamber, and a common means within said chamber for controlling delivery to said chamber of said mixture and for regulating the air supply through said inlet.

15. In a carburetor, a mixing chamber having an air inlet and a fuel inlet, a valve within said chamber controlling both of said inlets and means carried by said valve for deflecting the incoming air across the fuel inlet.

16. In a carburetor, a mixing chamber having an air inlet and a fuel inlet, a valve within said chamber rotatively controlling both of said inlets and having a single opening for registration with both of said inlets, and means carried by said valve in proximity to said opening for deflecting the incoming air across the fuel inlet.

17. In a carburetor, a mixing chamber formed with a row of fuel inlets and with an air admission port, a valve within said chamber rotatively controlling said fuel inlets and air ports, and a deflector member carried by said valve and compelling a flow of the incoming air across said row of fuel inlets.

18. In a carburetor, the combination with a mixing chamber having an opening to the atmosphere, of means for effecting a subdivided flow and delivery of fuel to said chamber.

ber, and means for heating said fuel in the course of its subdivided flow.

5 19. In a carburetor, the combination with a mixing chamber, of a plurality of passages leading to said chamber, means for delivering an excessively rich mixture to each of said passages, and a common means for heating said passages.

10 20. In a carburetor, the combination with a mixing chamber and a plurality of fuel passages leading to said chamber, of control means within said chamber for uncovering said passages in a definite succession, means for heating portions of all of said passages by exhaust gases, and means for electrically heating a portion of the passage initially uncovered by said control means.

15 21. In a carburetor, the combination with a heating chamber and means for flowing exhaust gases through said chamber, of a plurality of fuel tubes extended within said heating chamber and relatively positioned to expose them successively more fully to the exhaust gases as the latter increase in volume.

25 22. In a carburetor, the combination with a liquid fuel container having a plurality of restricted passages opening below the normal liquid level therein and extending above said level, of a mixing chamber, a corresponding number of passages leading from said mixing chamber to points adjacent the first named passages, a removable and replaceable member having restricted openings for connecting the passages of said fuel container 30 with the passages leading to the mixing chamber, and means for regulably admitting air to said openings.

35 23. In a carburetor, the combination with a liquid fuel container and a mixing chamber, of a plurality of restricted passages for the delivery of fuel from said container to said chamber, said passages having openings for the admission of air to form an initial rich mixture in said passages, a rotary valve 40 controlling said openings, a rotary valve in the mixing chamber controlling the admission thereto of a secondary supply of air, and means for independently actuating said rotary valves.

45 24. In testimony whereof I sign this specification.

CHARLES A. SAWTELLE.
